UNITED STATES PATENT OFFICE

CARMELO LAURIA, OF NEW YORK, N. Y.

DESIGN FOR A LAMP STAND

Application filed August 8, 1929. Serial No. 32,341. Term of patent 3½ years.

To all whom it may concern:

Be it known that I, CARMELO LAURIA, a subject of the King of Italy, residing at New York, in the county of Bronx and State of New York, have invented a new, original, and ornamental Design for Lamp Stands, of which the following is a specification, reference being had to the accompanying drawing, forming part thereof.

The figure is a perspective view of a lamp stand, showing my new design.

I claim:

The ornamental design for a lamp stand, as shown.

CARMELO LAURIA.
